CLAIM

The ornamental design for an electrical connector, as shown and described.

DESCRIPTION

FIG. 1 is a perspective view of a first embodiment of an electrical connector showing my design;

FIG. 2 is a left side elevation view thereof; the right side elevation view thereof being a mirror image;

FIG. 3 is a top plan view thereof;

FIG. 4 is a front elevation view thereof;

FIG. 5 is a rear elevation view thereof;

FIG. 6 is a bottom view thereof;

FIG. 7 is a perspective view of a second embodiment showing my design;

FIG. 8 is a left side elevation view thereof;

FIG. 9 is a top plan view thereof;

FIG. 10 is a front elevation view thereof;

FIG. 11 is a rear elevation view thereof;

FIG. 12 is a bottom view thereof; and,

FIG. 13 is a right side elevation view thereof.

The broken line showing of a portion of an electrical cable and male plug elements are for illustrative purposes only and form no part of the claimed design.
